UNITED STATES PATENT OFFICE.

DONALD S. BARROWS, OF ROCHESTER, NEW YORK.

DRAFT RIGGING.

Application filed April 22, 1926. Serial No. 103,908.

This invention relates to railway draft rigging, and, more particularly, to a friction shock-absorbing mechanism especially adapted for receiving and absorbing forces transmitted through the associated coupler of a car.

The principal object of my invention, generally considered, is to provide a friction draft gear especially adapted for use on railway cars where high capacity, ruggedness, economy of construction and low maintenance costs are desired.

Another object of my invention is to provide a friction draft gear especially adapted for use on railway cars where high capacity, easy release and high ultimate strength are desired.

A further object of my invention is the provision of a friction draft gear employing merely friction elements and plate springs, said springs performing the double function of absorbing the shocks by pressing the friction elements into engagement and effecting the release of the gear.

A still further object of my invention is to provide a friction draft gear wherein are utilized groups of curved plate springs which develop a strong resistance and induce a frictional resistance between cooperating friction elements and between each other upon operation of the gear.

Other objects of the invention will become apparent from the following specification.

Referring to the drawings illustrating my invention, the scope whereof is defined by the appended claims:

Figure 1 is a fragmentary vertical central longitudinal section of a railway draft rigging embodying my invention.

Figure 2 is a transverse vertical section on the line 2—2 of Figure 1 looking in the direction of the arrows.

Figure 3 is a horizontal sectional view of a modification of my invention.

Referring to the drawings in detail, like parts being designated by like reference characters, a friction draft gear 1 is illustrated, said gear in the embodiment shown in Figures 1 and 2 comprising a pair of friction casings 2, longitudinally spaced and opening toward each other and each comprising an end wall 3, side walls 4, a top wall 5 and a bottom wall 6. The end walls 3 are preferably formed with horizontally disposed wedge portions 7 inwardly extend-

ing toward each other and preferably arranged approximately midway between the top and bottom walls 5 and 6. These wedge portions are preferably formed by sloping the portions of the end walls above the mid portion downwardly and inwardly and the portion below said mid portion upwardly and inwardly to join with the downwardly and inwardly sloping portion and meet at an apex 8. The angle that the sloping portions make with the horizontal is preferably greater than the angle of friction between bodies of steel or cast iron, of which the parts of the gear may be made, so that release may be effected without the use of auxiliary release springs.

Positioned between the casings 2 is an intermediate follower 9 preferably of a height corresponding with that of the casings and formed with outwardly extending wedge portions 10 positioned and shaped to correspond with the wedge portions 7 on the casings. Enclosed in each casing between the same and the follower 9 is a pair of spring carriers 11 formed with normally abutting bases of bottom walls 12, side walls 13, and end walls 14. The bases or bottom walls 12 adjacent the end walls 14 are preferably sloped to correspond with the slope of the side walls of the wedges 7 and 10 so as to provide for the reception of said wedges between the flaring ends of the base portions 12 of the carriers 11. Said carriers 11 are preferably of a length corresponding to the inside length of the casings 2 so that, when the gear is fully compressed, the casings abut the intermediate follower 9 and provide a solid column for transmitting ultimate stresses which may be impressed on the gear when in service. The follower 9 may be cored out, as indicated at 15, for decreasing the weight thereof.

Supported by or continued in each carrier 11 is a group of preferably curved spring plates 16. Said plates, in the embodiment shown, are positioned with their concave sides toward the bases 12 of the carriers but it is obvious that the position thereof may be reversed if desired. For taking the wear off the springs 16 and distributing the wear on the casings 2, I preferably provide friction shoes or wear plates 17 fitting in the spring carriers 11 outwardly of the spring plates thereof and normally pressed into frictional engagement with the upper wall 5 and lower wall 6, respectively, of the as-

sociated casing 2. On account of the spring 16 being curved, more clearance is necessarily provided between the ends thereof and the associated carriers 11 than between the ends of the friction shoes or wear plates 17 and said carriers, the clearance with respect to the wear plates being relatively small, as indicated in the drawings, so as to reduce the amount of lost motion therebetween and 10 cause the maximum amount of movement between the wear plates and casings.

In the embodiment illustrated in Figures 1 and 2, the gear is shown with a pair of casings so as to be of a length corresponding 15 to a full A. R. A. gear but it is obvious that, if a shorter gear is desired, only one casing may be employed as illustrated in Figure 3. In Figures 1 and 2, the gear is shown associated with the standard fol- 20 lower attachments such as a horizontal yoke 18, a rear follower 19, a front follower 20 and a backstop 21. The casings and rear follower are shown supported on carrier irons 22 connected to the center sills 23 in 25 any desired manner (not shown). The yoke 18 at its rearward portion is shown supported by means of angle irons or clips 24, the vertical flanges of which are riveted or otherwise connected to the vertical webs of 30 the center sills 23 and the horizontal webs of which extend inwardly and underlie said yoke. The center sills are shown connected at their upper edges by means of a usual cover plate 25.

35 The operation of the gear is as follows: Upon draft forces being applied to the yoke 18, the rear casing 2 is moved toward the front casing to thereby cause the spring carriers 11 to ride forwardly and outwardly 40 on the wedge portions of the casings and intermediate follower 9, respectively, and cause a compression or flattening out of the plate springs 16 and the generation of friction between the wear plates or friction 45 shoes 17 and the adjacent walls of the casings. It will be apparent that friction is generated between the wedges and the carriers, between the friction plates themselves and the engaging bases of the carriers, be- 50 tween the wear plates 17 and the carriers and between said wear plates and the casings. As the intermediate follower 9 ap- 55 proaches both casings, the spring carriers approach the corresponding end walls of the casings at half the speed because they, at the same time, approach the intermediate follower at a corresponding speed so that the motion between the friction shoes or wear plates and the casings is approxi- 60 mately half that of the motion between the intermediate follower 9 and each casing. Upon buffing forces being applied to the front follower 20, the front casing 2 moves toward the rear casing but otherwise the gear 65 functions in a corresponding manner.

Referring to the embodiment of my in- 70 vention illustrated in Figure 3, I have shown a gear approximately one-half the length of the gear shown in the first two figures and employed with a vertical yoke 26 and backstop 27 without any other rear follower than that comprising a follower 28 which is formed with a wedge-shaped por- 75 tion 29 corresponding to the wedge-shaped portions 7 and 10 of the previous embodi- 80 ment but vertically disposed. In other respects the casing 2^a, the spring carriers 11^a, spring group 16^a and wear plates 17^a are identical with the casings, carriers, spring groups and wear plates of the first 85 embodiment except that they are positioned at an angle of 90° with respect thereto. It is obvious, however, that this shortened gear may be used in the same position as the gear of the first embodiment and the operation is 90 similar to the operation of said first men- 95 tioned gear.

From a consideration of the foregoing, it will be apparent that the tandem arrange- 95 ment disclosed in Figures 1 and 2 is espe- 100 cially adapted for a full A. R. A. gear. To replace the 18½ inch Cardwell gear or to interchange with any 20½ or 22¼ inch gear, two shorter casings and their asso- 105 ciated parts might be used, if desired, or one unit with an auxiliary spring in tandem. To replace twin springs, a short unit could be provided embodying my invention and the rear follower 19 could be omitted. On account of the limited space, leaf or plate 110 springs are practically necessary for a gear of this sort if a high capacity is to be se- 115 cured. If desired, special means may be provided for insuring that the spring car- 120 riers or cages stay absolutely parallel but, as will be apparent, they will remain sub- 125 stantially so without any auxiliary devices.

Having now described my invention, what I claim is:

1. In a draft gear, in combination, a fric- 110 tion casing formed with a wedge-shaped inner portion, a plurality of spring carriers enclosed in said casing and formed with friction faces cooperating with the wedge- 115 shaped portion on the casing, a plurality of spring plates contained in said carriers, a follower formed with a wedge-shaped portion complementary to the wedge-shaped portion on the casing and engaging corre- 120 sponding portions on the spring carriers 125 whereby, when the gear is compressed, the spring carriers move away from each other and compress the spring plates, and wear plates positioned between said spring plates and the adjacent sides of the casing and mov- 130 able with said carriers when the gear is operated.

2. In a draft gear, in combination, a casing formed with an inner wedge-shaped exten- 130 sion on the end wall thereof, a plurality of

carriers enclosed in said casing and formed with faces sloped for cooperative engagement with the wedge-shaped extension, curved spring plates supported in said carriers, means disposed between said casing and springs for protecting the latter from wear, a follower formed with a wedge-shaped extension corresponding to the wedge-shaped extension on the casing and engaging correspondingly formed portions on the spring carriers, whereby said carriers are separated when the follower moves toward the casing.

3. In a draft gear, in combination, a casing formed with an end wall, side walls and top and bottom walls, a wedge-shaped extension formed on the inner side of the end wall, spring carriers each formed with a bottom wall and side walls, the ends of the bottom wall being sloped at an angle corresponding to the wedge-shaped portion on the carrier and engaging said wedge-shaped portion one on each side thereof, a group of curved spring plates longitudinally disposed in said carriers, a follower of a height corresponding with that of the casing formed with a wedge-shaped extension complementary to the wedge-shaped extension on the end wall of the casing and engaging the opposite ends of the spring carriers whereby, when the casing and follower move toward each other, the spring carriers are wedged apart against the spring action between the walls of the casing and the bottom walls of the carriers to flatten the spring plates.

4. In a draft gear, in combination, a friction casing formed with a wedge-shaped inward extension, a pair of transversely arranged carriers in said casing and formed with friction faces engaging opposite sides of the wedge-shaped extension, a group of curved spring plates in each carrier, friction shoes receivable in said carriers exterior to said spring plates for protecting the latter from wear, a follower formed with a wedge-shaped extension corresponding with that on the casing and correspondingly engaged with the spring carriers whereby the wedge portions act to separate the carriers upon relative approach of the casing and follower.

5. In a draft gear, in combination, a friction casing formed with a wedge-shaped inward extension, a pair of transversely arranged carriers in said casing and formed with friction faces engaging opposite sides of the wedge-shaped extension, a group of curved spring plates in each carrier, a follower formed with a wedge-shaped extension corresponding with that on the casing and correspondingly engaged with the spring carriers whereby the wedge portions act to separate the carriers upon relative approach of the casing and follower, and friction shoes positioned in the carriers outwardly of

the spring plates and frictionally engaging the adjacent walls of the casing when the gear is operated.

6. In a draft gear, in combination, a friction casing formed with an end wall, side walls and upper and lower walls, the intermediate portion of said end wall being provided with a downwardly and inwardly sloping portion and an upwardly and inwardly sloping portion meeting said downwardly and inwardly sloping portion approximately midway between the upper and lower walls, a follower positioned adjacent the open end of the casing and formed with correspondingly sloping walls extending toward the walls of the casing, a pair of spring carriers formed with normally abutting bases, the ends of which are sloped and engage the sloping walls on the casing and follower with which they correspond, curved spring plates positioned in said carriers, and friction shoes mounted in said carriers outwardly of said springs and frictionally engaging the upper and lower walls, respectively, of the casing.

7. In a draft gear, in combination, a plurality of longitudinally spaced casings opening toward each other and each formed with an inner wedge-shaped extension on the end wall thereof, a plurality of carriers enclosed in each casing and formed with normally abutting bases the ends of which are correspondingly sloped for frictional engagement with the wedge-shaped extensions, curved spring plates supported in all of said carriers, an intermediate follower formed with outwardly extending wedge-shaped portions corresponding to the wedge-shaped extensions on the casings and engaging correspondingly sloped friction surfaces on the spring carriers, whereby said carriers are separated when the casings are moved toward each other.

8. In a draft gear, in combination, a pair of spaced friction casings formed with wedge-shaped extensions from the inner surfaces of the end walls thereof, a pair of transversely arranged carriers in each casing and formed with friction faces engaging opposite sides of the wedge-shaped extensions, a group of curved plate springs in each carrier, a follower disposed intermediate the casings and formed with wedge-shaped portions corresponding with and extending toward the wedge-shaped extensions on the casings and engaging correspondingly formed friction faces on the carriers, whereby said wedge-portions act to separate the carriers upon relative approach of the casings, said casings being adapted to abut the follower upon full closure of the gear.

9. In a draft gear, in combination, a pair of friction casings each formed with end walls, side walls and upper and lower walls, the intermediate portion of said end walls

being formed as downwardly and inwardly sloping portions meeting upwardly and inwardly sloping portions approximately midway between the upper and lower walls,
5 a follower positioned between said casings adjacent the open ends thereof and formed with correspondingly sloping walls extending outwardly toward the sloping walls of the casings, a pair of spring carriers positioned in each casing and formed with bases normally abutting approximately midway between the upper and lower walls of the casings, the ends of said bases being sloped to engage the sloping walls on the casing
10 and followers with which they correspond, curved spring plates positioned in said carriers and friction shoes mounted in said carriers outwardly of said springs and frictionally engaging the upper and lower walls, respectively, of the casings.

10. In a railway draft rigging, in combination with movable elements for applying forces received by said rigging, a draft gear comprising a friction casing formed with
25 a wedge-shaped inner portion, a plurality of spring carriers enclosed in said casing and formed with friction faces cooperating with the wedge-shaped portion on the casing, a plurality of spring plates contained in said carriers, a follower formed with a wedge-shaped portion complementary to the wedge-shaped portion on the casing and engaging corresponding portions on the spring carriers whereby, when the gear is
30 compressed, the spring carriers move away from each other and compress the spring plates, and wear plates positioned between said spring plates and the adjacent sides of the casing and movable with the spring plates when the gear is operated.

11. In a railway draft rigging, in combination with movable elements for applying forces received by said rigging, a draft gear comprising means exterior of said spring plates for frictionally engaging said casing and protecting said spring plates from wear, a casing formed with an end wall, side

walls and top and bottom walls, a wedge-shaped extension formed on the inner side of the end wall, spring carriers each formed with a bottom wall and side walls, the ends of the bottom wall being sloped at an angle corresponding to the wedge-shaped portion on the carrier and engaging said wedge-shaped portion one on each side thereof, 50 a group of curved spring plates longitudinally disposed in said carriers, a follower formed with a wedge-shaped extension complementary to the wedge-shaped extension on the end wall of the casing and engaging the opposite ends of the spring carriers whereby, when the casing and follower move toward each other, the spring carriers are wedged apart against the spring action between the walls of the casing and the bottom 55 walls of the carriers to flatten the spring plates.

12. In a railway draft rigging, in combination with movable elements for applying forces received by said rigging, a draft gear 70 comprising a friction casing formed with a wedge-shaped inward extension, a pair of transversely arranged carriers in said casing and formed with friction faces engaging opposite sides of the wedge-shaped extension, a group of curved spring plates in each carrier, a follower formed with a wedge-shaped extension corresponding with that on the casing and correspondingly engaged with the spring carriers whereby the 75 wedge portions act to separate the carriers upon relative approach of the casing and follower, and friction shoes positioned in the carriers outwardly of the spring plates and frictionally engaging the adjacent walls 80 of the casing when the gear is operated, said casing being formed to completely receive the carriers and the elements contained therein, whereby the follower abuts the adjacent end of the casing when the gear is completely compressed.

In testimony whereof I affix my signature.

DONALD S. BARROWS.
